(57) **CLAIM**

The ornamental design for a pair of chopsticks, as shown and described.

DESCRIPTION

FIG. 1 is a front and side perspective view of a pair of chopsticks showing my new design;

FIG. 2 is a front side plan view thereof;

FIG. 3 is a back side plan view thereof;

FIG. 4 is a right side plan view thereof;

FIG. 5 is a left side plan view thereof;

FIG. 6 is an enlarged top plan view thereof;

FIG. 7 is an enlarged bottom plan view thereof; and,

FIG. 8 is an enlarged right side view of the pair of chopsticks for ease of illustration as viewed from the bottom of FIG. 4.
